SURFACE ORNAMENTATION OF WALLS, &c.

No. 16,528.

Patented Feb. 16, 1886.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,528, dated February 16, 1886.

Application filed November 13, 1885. Serial No. 189,760. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part thereof.

My design consists of the surface configuration having the appearance of a number of overlapping bars or boards, as A B. Upon the edge of each bar appears a series of regular scallops, C. The said edge is also inwardly beveled or inclined, as at D. The scallops of one bar, as A, appear directly opposite the points of intersection or meeting of the scallops of the adjacent bar, as B. Upon the face of each bar and between the scallops are transverse scores or chaunes E.

I claim—

1. The design for surface ornamentation of walls, &c., substantially as herein shown and described, which consists in bars A B, the bar A having the appearance of overlapping the bar B, the said bars having beveled edges D and scallops C along said edges. 20

2. The design for surface ornamentation of walls, &c., substantially as herein shown and described, which consists in bars A B, the bar A having the appearance of overlapping the bar B, the said bars having beveled edges D and scallops C along said edges, and on their face channels E. 25
